PATENTED DEC. 4, 1906.

T. R. NICHOLAS.

SIGNAL.

APPLICATION FILED MAY 10, 1906.

UNITED STATES PATENT OFFICE.

THOMAS R. NICHOLAS, OF CARTHAGE, MISSOURI.

SIGNAL.

No. 837,336.

Specification of Letters Patent.

Patented Dec. 4, 1906.

Application filed May 10, 1906. Serial No. 316,051.

To all whom it may concern:

Be it known that I, THOMAS R. NICHOLAS, a citizen of the United States, and a resident of Carthage, in the county of Jasper and State 5 of Missouri, have invented a new and useful Improvement in Signals, of which the following is a specification.

A principal object of my invention is to provide a signal principally for use on rail- 10 ways which may be employed as the regular signaling system or may be in addition there- to. It is preferably so arranged that a danger-signal may be set from a distant point at any time by an operator and may also be 15 arranged so that certain causes—such, for in- stance, as the burning or washout of a bridge— will automatically set the signal.

The signal is preferably electrically oper- 20 ated, and, as will hereinafter appear, an open or closed circuit may be employed.

The features and advantages of my inven- 25 tion are hereinafter more particularly set forth in connection with the description of the accompanying drawings, which illustrate an exemplification of the invention.

Figure 1 is a sectional view of the signal apparatus proper, which I term, for convenience, a "signal-stand." The figure also includes a diagram of the electrical circuit; 30 Fig. 2, a detail of the electrical connection; Fig. 3, a modification of the trip mechanism, and Fig. 4 a detail of the torpedo-placing mechanism.

1 is the signal-stand; 2, an axle in the up- 35 per part of the stand; 3, a semaphore-arm borne upon the axle exterior to the stand; 4, a counterweight to actuate the semaphore and other parts, which may simply be a weight or may be a mounting for a night-sig- 40 nal glass; 5, a tooth carried by the axle within the stand and serving as a detent; 6, a latch having a hook at one end engaging the tooth and having the other end 7 adapted to be struck by a hammer, as later described; 8, 45 a stop to limit the motion of the latch; 9, an arm upon the axle; 10, a vertical connecting- rod within the stand; 11, a shaft near the bot- tom of the stand and which may have bear- 50 ings in each side thereof; 12, a bell-crank 55 borne on shaft 11, of which one arm is piv- oted to connecting-rod 10; 13, another link or horizontal connecting-rod, one end of which is pivoted to the other end of bell- 60 crank 12; 14, a torpedo-rod reciprocable in suitable supports; 15, a pivotal connection 65 thereon for the connecting-rod 13; 16, a tor- 70

pedo-fork on the outward end of rod 14, bearing one or more torpedoes 17; 18, a door closing the outer lower end of the stand and which when the torpedoes are thrust forward 60 may be thereby raised. Other mechanism may in some cases be provided in raising the door and preventing its contact with the tor- pedoes.

The mechanism so far described will op- 65 erate as follows: If the latch 6 is operated so as to raise the hook, the tooth 5 will be freed, and the weight 4 will thereupon rotate the axle 2 in an anticlockwise direction, bringing the semaphore into active or danger position. 70 The connecting-rod 10 will be thrown down and the bell-crank moved in an anticlockwise direction, throwing connecting-rod 13 to the right and thrusting the torpedo-rod 14 with the torpedoes out of the stand, the door 18 75 being incidentally raised. The torpedoes are thus brought over the rail and in position to be acted upon by the wheels of a passing train. An interconnected visual and audible signal is thus provided, meeting all conditions 80 of traffic.

To reset the parts after they have been put in danger position, a replacing-handle 19 is provided, which may be directly on the rod 10 or may be a part of a lever 20, suitably 85 mounted in the stand and connected to the rod. Access to the replacing-handle is pref- erably had through a door 21 in the stand, which may be locked, as shown, to prevent meddling with the apparatus by an unau- 90 thorized person.

25 is an electromagnet of any desired style located within the stand; 26, a hammer conveniently pivoted at one end to the stand and so located that it may be retained in 95 raised position by the armatures of the mag- nets and that when released its head may strike the arm 7 of the latch 6.

27 represents the electrical circuit, which is energized by a source of power 28 and suitably 100 grounded.

29 is an exemplification of a key or other device by which the signal may be arbitrarily operated.

The mechanism so far as described is to 105 operate on closed circuit. So long as the circuit is closed the magnet, as shown, at- tracts the hammer and holds it inoperative. If, however, the circuit is broken from any cause, the magnet is deenergized, the ham- 110 mer drops, striking the arm 7 of the latch, and the signal is set, as before described. Bv

this arrangement any accidental derangement of the circuit will set the danger-signal. By means of the cut-out 29 the signal may also be set at any time by an operator from 5 a distant point. A number of cut-outs may of course be provided, and one or more signals may be in circuit with one or more of the cut-outs, so that the signals may be operated in a manner which the conditions may require.

It is obvious that if the electrical line crosses a bridge the line-wire is liable to destruction if the bridge is seriously injured, as by fire or water, (floods,) and in such a 15 case the circuit is broken and the safety-signals, which may in this case be placed one on each side of the bridge, are set. This arrangement may be applied to such a railway device as a lift or swing bridge, which is designated by numeral 30. The track may part at the point 31 when the draw is raised, and, as best seen in Fig. 2, at this point an electrical connection for the line-wire is conveniently provided, consisting of contacts 25 32 33. It will be obvious that when the draw is raised the circuit will be broken and the signal set.

As stated, the device may also be worked with an open circuit. In Fig. 3 a proper arrangement is shown. Here the detent or tooth is designated by 5^a and is conveniently placed at the end of arm 9. 6^a is the latch, which in this case is pivoted at one end. The parts are shown in the normal or clear-track position, the line-circuit being open. To set the signal, the circuit may be closed 30 as by a cut-out, such as has been described, and the magnet becoming energized will attract the latch 6^a, releasing the detent and allowing the signal to go to the danger position, as above described.

When the closed-circuit system of operation is employed, it will be observed that if for any reason the circuit has been interrupted 45 and the signal thereby caused to move to the danger position any effort to reset the signal to safety position before the cause of breaking of the circuit has been removed will be ineffectual, because the hammer 26 will still hold the catch 7 out of engagement with the tooth 5, and the semaphore will therefore move to the danger position as soon as the handle 19 or rod 10 is released. Now if the circuit has been broken by the operator moving the cut-out 29 or by pressing a button, 50 which may take the place of the cut-out, the operator will naturally return the cut-out to the position shown in the drawings or will release the button, thereby again completing the circuit, and the hammer will be raised by the magnet. A member of the crew of the train which has been stopped by the danger-signal upon attempting to reset it will find 55 that the catch is operative and holds the signal in safety position. If, on the other hand,

the signal has been set by the destruction of a part of the line-wire—as, for instance, by the burning of a bridge—the attempts to reset the signal will be futile, for the reason stated. This enables the train-crew to distinguish between causes which give rise to the danger condition, and they can act accordingly. If the indications are that the signal has been set by disaster on the line, such as a burned bridge, the train can proceed toward the point of trouble.

It will be understood by those versed in the art without particular description how the apparatus is placed in working position in proper relation to the railroad-track.

I do not intend to limit myself to any of the details shown, but contemplate any variations which may come within the spirit of my invention.

I claim—

1. A signal comprising a semaphore and a torpedo-placing device, connections between the two, means constantly tending to throw the signal to danger position, a detent normally retaining the signal in safety position, 90 an electromagnet normally energized by a closed circuit, and a weight attracted by the magnet and adapted to fall and release the detent by striking it a positive blow when the circuit is broken, thereby permitting the signal to go to a danger position.

2. In a signal, a shaft, a semaphore thereon, a tooth thereon and a detent, a counter-weight connected with the semaphore urging same to the danger position, means including an electromagnet for positively withdrawing the detent and allowing the semaphore to move to danger position, a reciprocable bar having means for carrying a torpedo, a link connected to the bar, a link connected to an arm on said shaft, and a bell-crank connecting the links so that the torpedo-bar is caused to move in unison with the semaphore.

3. In a signal, the combination of a signal-stand having an upright portion and a horizontal bottom portion which has an opening adjacent to the track, a door covering said opening, a reciprocating member carried in the bottom portion and having a torpedo-carrying member so placed that when in extended position it will place a torpedo directly over the adjacent rail, an oscillating shaft in said upper portion, a semaphore thereon, a tooth on said shaft, a detent engaging the tooth, positive means including an electromagnet for withdrawing the detent, a counterweight for forcing the semaphore to danger position when the detent is withdrawn, and linkage intermediate the shaft and reciprocating member for moving said member in unison with the shaft.

4. In a signal, the combination of a signal-stand having an upright portion and a horizontal bottom portion which has an opening adjacent to the track, a door covering said

opening, a reciprocating member carried in the bottom portion and having a torpedo-carrying member so placed that when in extended position it will place a torpedo directly over the adjacent rail, an oscillating shaft in said upper portion, a semaphore thereon, a tooth on said shaft, a detent engaging the tooth, positive means including an electromagnet for withdrawing the detent, a counterweight for forcing the semaphore to danger position when the detent is withdrawn, linkage intermediate the shaft and reciprocating member for moving said member in unison with the shaft, and a connection between said reciprocating member and the door, such that when said member is extended the door is raised in advance of the torpedo carried by the member so that the torpedo carried by the member will not contact with the door.

5. In a signal, the combination of a stand having an upright portion and a horizontal bottom portion, the latter portion having an opening adjacent to the track and covered by a door, a rock-shaft in the upper portion, a tooth thereon, a detent engaging the tooth, a weight arranged to strike the detent and an electromagnet for normally holding the weight in inactive position, a bar mounted to reciprocate in guides in the bottom portion, a torpedo-fork secured to the bar and one or more torpedoes carried by the fork, a bell-crank, a link connecting said shaft with the bell-crank and another link connecting the bell-crank with said bar, and link connection between the bar and the door for opening the door in advance of the movement of the torpedo-fork, a weight connected with the movable part for throwing the semaphore and torpedo-fork to danger position, and means for controlling the electrical circuit of said magnet.

6. In a signal, a semaphore, a torpedo-carrier, the semaphore and torpedo-carrier being normally in safety position, and means for moving the semaphore and carrier to danger position comprising an electromagnet, a striker controlled thereby, and an electrical circuit connected with the magnet.

7. In a signal, a semaphore, a torpedo-carrier, the semaphore and torpedo-carrier being normally in safety position, and means for moving the semaphore and carrier to danger position comprising an electromagnet, a striker controlled thereby, and an electrical circuit connected with the magnet, the mechanism operating upon a change in the condition of the electrical circuit to cause the striker to deliver a positive blow and cause the semaphore and carrier to go to danger position.

8. In a signal, a semaphore, a detent normally holding the semaphore in safety position, means for moving the semaphore to danger position, means including an electromagnet for positively withdrawing the detent causing the semaphore to move to danger position, and a torpedo-carrier connected to move in unison with the semaphore.

9. In a signal, the combination of a housing adjacent to a railway-rail, a torpedo-carrier normally within the housing, a pivoted closure for the housing, means for projecting the carrier from the housing and into operative relation to the rail, and links connecting the carrier and closure for opening and closing the closure to permit the necessary movement of the carrier.

In testimony whereof I have affixed my signature in the presence of two witnesses.

THOMAS R. NICHOLAS.
